(57) **CLAIM**

The ornamental design for a compression stop and coupling wrench, as shown and described.

DESCRIPTION

FIG. 1 is a perspective view of a compression stop and coupling wrench, showing our new design;
FIG. 2 is a top elevation view thereof;
FIG. 3 is a right side elevation view thereof;
FIG. 4 is a left side elevation view thereof;
FIG. 5 is a front elevation view thereof;
FIG. 6 is a rear elevation view thereof; and,
FIG. 7 is an exploded perspective view showing the two parts of the compression stop and coupling wrench of our new design.
